UNITED STATES PATENT OFFICE

HARRY P. TROENDLY, OF NEW YORK, N. Y., ASSIGNOR TO DUNBAR-GIBSON, INC., OF NEW YORK, N. Y., A CORPORATION OF DELAWARE

DESIGN FOR A SUPPORT FOR LAWN SPRINKLER

Application filed April 19, 1933. Serial No. 47,840. Term of patent 3½ years.

To all whom it may concern:

Be it known that I, HARRY P. TROENDLY, a citizen of the United States, residing at New York, county of New York, State of New York, have invented a new, original, and ornamental Design for a Support for Lawn Sprinkler, of which the following is a specification, reference being had to the accompanying drawing, forming part thereof.

Fig. 1 is a plan view of the support for lawn sprinkler showing my new design;

Fig. 2 is a side elevational view of the support for lawn sprinkler, and

Fig. 3 is a bottom view of the support for lawn sprinkler.

I claim:

The ornamental design for a support for lawn sprinkler, as shown.

HARRY P. TROENDLY.
